INVENTOR,
George W. Huckabay
BY
Frank A. Fouts
ATTORNEY,

UNITED STATES PATENT OFFICE.

GEORGE W. HUCKABAY, OF GARFIELD, LOUISIANA.

CANE-MILL.

SPECIFICATION forming part of Letters Patent No. 398,401, dated February 26, 1889.

Application filed September 12, 1888. Serial No. 285,207. (No model.)

To all whom it may concern:

Be it known that I, GEORGE W. HUCKABAY, a citizen of the United States, and a resident of Garfield, in the parish of Caddo and State of Louisiana, have invented certain new and useful Improvements in Cane-Mills, of which the following is a specification.

This invention relates to that class of mills in which a yielding pressure is given to one of the rollers to provide for the passage of cane of different thickness; and it has for its objects to provide a new and improved combination of devices for effecting this object, as will be hereinafter described, and particularly pointed out in the claims.

Reference is herein had to the accompanying drawings, forming part of this specification, in which similar letters of reference indicate corresponding parts in all the figures.

20 Figure 1 is a plan view of a construction embodying my invention. Fig. 2 is a partial sectional side elevation, and Fig. 3 is a section on the line $\alpha\alpha$ of Fig. 2.

A base-block, A, is provided with two openings, A' A², for the reception of roller-journals, the upper side of said block being provided with a groove, A³, extending from one end of the block to the opening A². A top block, B, is constructed substantially the same 30 as the block A—that is to say, the block B is provided with two openings, B' B², and also provided with a groove, B³, on its upper side, extending from one end of the block to the opening B². The blocks A B are connected 35 at one end by a block, a, and connected at the opposite end by an H-shaped block, b. A roller, C, is provided with journals C', said journals being engaged in the openings A' B'. A sliding block, G, is mounted in the groove 40 B³, and a sliding block, H, is mounted in the groove A³. The inner ends of each block G H is recessed, so as to fit the journals D' of the roller D. A rabbeted movable block, I, lies partly outside of and partly between the 45 blocks G H, the latter blocks, G H, lying in the rabbeted parts of the block I aforesaid.

J is a lever fulcrumed at J' in the recess J² of the block b. K is also a lever fulcrumed at K' in the recess K² of said block. The 50 lever J is provided with a series of notches,

J⁴, on its upper side, and the lever K is provided on its under side with a series of notches, K⁴. A bar, L, is provided on its upper side, near its inner end, with a notch, L', also provided on its upper outer side with a 55 series of notches, L², and the under side of said bar, near its inner end, is provided with a series of notches, L³. A link, M, engages the notches J⁴ and L³ in the lever J and bar L, respectively, and a link, N, engages the 60 notch L' in the bar L and the notches K⁴ in the lever K.

O is a weight provided with a link or hook, P, said hook being engaged with one of the notches L² in the outer upper side of the bar L. 65

The operation of my invention is as follows: When the parts are in the position shown in Figs. 1 and 2, the bar L and levers J K are connected by the links M N, and the said parts J K L M N form a compound lever. The 70 weight O, with its link P, draws down on the outer end of the bar L, causing the link M to force down the outer end of the lever J, the link N forcing up the outer end of the lever K. This action causes the inner ends of the 75 levers J K to press against the outer side of the movable block I, and thereby force the blocks G H inward, so as to press the inner ends of said blocks G H against the journals D', thereby forcing the roller D nearer the 80 companion roller C. Any desired pressure may be brought to bear against the journals D' by adjusting the weight O and its link on the bar L. Of course this weight can be increased or diminished to suit the character of 85 work to be performed. A further adjustment of the levers may be effected by means of the links M N and lever-notches.

Having thus described my invention, I claim as new and desire to secure by Letters Patent 90 of the United States—

1. The combination, with the grooved blocks A B, connected at one end by a block, a, and at the other end by an H-shaped block, b, of the rollers C D, one having its journal adjustably located in its bearings, the sliding blocks G H, the rabbeted block I, bearing 95 against the outer ends thereof, the cam-levers J K, bearing against the block I and fulcrumed to the block b, and the weighted lever L, con- 100

nected to the levers J K by means of links M N, substantially as and for the purpose specified.

2. The combination, with the sliding block I, the blocks G H, and shaft D', of the notched cam-levers J K and notched lever L, and the links M N, connecting said notched levers, substantially as specified.

Signed at New York, in the county of New York and State of New York, this 10th day of September, A. D. 1888.

GEORGE W. HUCKABAY.
